[57] CLAIM

The ornamental design for a bingo equipment container, as shown and described.

DESCRIPTION

FIG. 1 is a perspective view of a bingo equipment container, in open position, showing my new design;
FIG. 2 is a perspective view thereof, with top cover;
FIG. 3 is a top plan view of FIG. 1;
FIG. 4 is a bottom plan view of FIG. 1;
FIG. 5 is a front elevation of FIG. 1;
FIG. 6 is a rear side elevation of FIG. 1;
FIG. 7 is a right side elevation of FIG. 1, the left side elevation being a mirror image;
FIG. 8 is a sectional elevation taken along line 8—8 of FIG. 3; and
FIG. 9 is a sectional elevation taken along line 9—9 of FIG. 3.

FIG. 1

FIG. 2

FIG. 5

FIG. 6

FIG. 7

FIG. 8

FIG. 9
